PICTURE HOOK

Louis E. Frey, Albany, N. Y., assignor, by mesne assignments, to Norman A. Henderson, Albany, N. Y.

Application July 27, 1940, Serial No. 347,873

5 Claims. (Cl. 248—32)

The present invention relates to a device for supporting pictures and other articles and relates more particularly to a hook for supporting pictures and the like on walls.

In the normal practice of hanging articles such as pictures, a cord or wire is affixed to the picture, or to the frame in which it is mounted, and the cord or wire is supported from a hook suitably anchored to the wall. Hook devices heretofore employed were unsatisfactory for the reason that they did not prevent slippage between the cord or wire and the hook device. Accordingly, the picture suspended from such hook devices tended to tip out of its proper position.

Certain of the prior hook devices are provided with means for setting up resistance to slippage. However, this resistance to slippage depends upon the friction between the hook device and the cord or wire and is not effective in preventing the tipping of the pictures.

It is an object of this invention to provide an improved picture hook construction which will be free from the above-mentioned and other disadvantages, and which will be especially simple and durable in construction, efficient in operation and inexpensive in cost.

In one aspect my invention comprises a hook device so constructed as to provide tapered slots which permit of the wedging in of the cord or wire therein, the weight of the picture on the cord or wire assisting in maintaining the cord or wire in the slots and effectively preventing any slippage. The slots are so formed as to permit of the easy positioning of the cord or wire on the hook.

Other objects of this invention, together with the details of construction and combinations of parts, will appear from the following detailed description and will be pointed out in the appended claims.

In the accompanying drawing wherein the preferred embodiments of my invention are shown,

Figure 1 is a side elevational view of a hook device constructed in accordance with my invention, partly in section to show the manner in which the nail is held in the hook device,

Figure 2 is a front elevational view of the same,

Figure 3 is a side elevational view of modified form of my hook device, and

Figure 4 is a front elevational view of the hook device shown in Figure 3.

Like reference numerals designate like parts throughout the several views of the drawing.

Referring now to Figures 1 and 2 of the drawing, reference numeral 5 generally indicates a web the upper portion of which is bent over at 7 to form

a loop, as shown. One side of the loop is provided with a hole 11, and the web is provided with with an opening 12 in diagonal alignment with the hole 11, as viewed in Fig. 1, to receive the nail 9. A tongue 13 integral with the web 6 is adapted to contact with the free edge 15 of loop to press the same against the nail to hold it in position both before and after the hook device is fastened to the supporting structure.

The lower edge of the web 6 is curled over to form a loop 16, the free end 17 of which is at the bottom 18 of the loop and is spaced from the main portion of the web 6. The side edges are formed with integral wedge-shaped projections 19 which are adapted to be bent at right angles to the main portion of the web and to form with portion 21 of the loop tapering slots 22 for the reception of the cord or wire of the picture being suspended.

The hook device is preferably made of a spring metal whereby the free end of the loop 16 will yieldingly and resiliently press against the cord or wire therein further holding the same in the tapered slots 22.

In Figures 3 and 4 there is shown a modification of the tapered slot construction in which the lower portion of the web 6 is bent rather sharply at 23 to form a tongue 24 flaring away from the main body of the web. This construction also forms tapering slots 25 having one rigid and one somewhat yielding and resilient side between which the cord or wire is received and held.

It will be noted that the opposite sides of the wire receiving slots 22 and 25 are not in exactly opposed relation. That is to say, the portions 21 and 24 are between or slightly offset from the wedge shaped portions 19. By this construction, slight but comparatively sharp bends are made in the cord or wire as it is pulled down into engagement with the sides of the slots which serve to prevent slippage of the cord or wire and yet do not prevent its being freely raised in a vertical direction out of engagement with the slots when it is desired to remove the picture from the hook.

It is to be understood that the foregoing detailed description is merely given by way of illustration and that many variations may be made therein without departing from the spirit of my invention.

Having described my invention, what I claim as new and desire to secure by Letters Patent is:

1. A hook device of the character described comprising a flat, elongated web having oppositely disposed portions at the edges thereof angularly disposed to the plane of said web; said

web being bent along a line adjacent said angularly disposed portions and having its free end disposed to form with said portions a hook adapted to receive a picture wire.

2. A hook device of the character described formed from an elongated strip of somewhat resilient material and provided near the end forming the top thereof with a nail receiving passage for securing said device to a wall; said device comprising a substantially flat, web portion adapted to lie adjacent said wall, oppositely disposed marginal portions of said web at the bottom thereof being bent out to lie in planes substantially perpendicular to said web, and that portion of said strip between the bottom of said web and the adjacent free end thereof being bent outwardly and upwardly from the bottom of said web to form with said bent out marginal portions a hook adapted to receive a picture wire.

3. A hook device of the character described comprising a flat metal strip having one portion thereof forming the bottom of said device bent to form with an adjacent portion of said strip a hook adapted to receive a picture wire, the opposite marginal edge portions of that part of said strip forming one side of said hook being angularly disposed to the plane of said part of said strip and extending outwardly therefrom substantially to the opposite side of said hook at the bottom thereof and presenting edges of said strip for engagement by said wire; whereby said wire

will be engaged by one side of said hook at two spaced points and by the other side of said hook between said points.

4. A hook device of the character described formed from an elongated strip of somewhat resilient material and provided with a nail-receiving passage whereby said device may be secured to a wall; said device comprising a web portion adapted to lie adjacent said wall, oppositely disposed marginal portions of said web at the bottom thereof being angularly disposed to the plane of said web and extending outwardly therefrom, and a narrower portion of said strip extending outwardly from said web portion at the bottom thereof being disposed at least in part between and closely adjacent said angularly disposed portions of said web to form therewith a wire-receiving hook.

5. A picture hook of the character described comprising an elongated web portion provided with a nail-receiving passage for securing said device to a wall, a portion integral with and narrower than said web portion and extending outwardly therefrom in the form of a substantially closed loop with one side thereof adjacent said web, and other portions of said web adjacent said loop extending outwardly from said web at each side of said loop to form therewith a hook adapted to receive and frictionally engage a picture wire.

LOUIS E. FREY.
